FLOOR MAT

Bobby F. Griffin, 1209 Norway St.,
Bristol, Va. 24201

Filed May 18, 1966, Ser. No. 2,343

Term of patent 14 years

(Cl. D9—6)

I claim:

The ornamental design for a floor mat, substantially as shown.
